UNITED STATES PATENT OFFICE.

KARL HEINRICH MEIER, OF ZURICH, SWITZERLAND.

OVERWINDING PREVENTER.

Application filed September 29, 1925, Serial No. 59,333, and in Switzerland September 3, 1925.

My invention relates to apparatus for winding up watches or clocks on motor vehicles, especially on motor cars. With these watches or clocks it happens frequently that they stop in consequence of not being wound up. According to my invention this drawback is obviated by using the rotations of the motor for winding up the watch spring. In my improved apparatus any part connected to the motor and rotated by the same is connected to the watch spring by means of an equalizing device of any suitable kind, for instance by means of a differential gear of any suitable construction. In my improved apparatus I prefer to use as such rotating part the flexible shaft driving the mileage or speed indicator, however any part rotated by the motor could also be used.

In the drawing accompanying and forming a part of this application I have illustrated several forms in which my invention may be embodied, although it will be understood that the illustrations are not intended to be exhaustive of the manifold forms this invention may take.

Fig. 1 is a side elevation of a construction adapted to put the invention into effect; Fig. 2 is a side elevation showing a modified form of a detail. Fig. 3 is a similar view showing still another modification of the same detail.

In the drawings only so much of the completed apparatus is shown as to enable one skilled in the art to understand my invention.

In the form shown in Fig. 1, 1 designates the usual flexible shaft driving the mileage or speed indicator. The shaft 1 is mounted to rotate in a support 1' and carries a spur bevel wheel 2 secured thereon. The wheel 2 meshes with a bevel wheel 3, which is secured to a shaft 4 mounted to rotate in suitable bearings 4', which are fast on the support 1'. A toothed wheel 5 is secured to the shaft 4 and meshes with a toothed wheel forming one part with the conical pinion 8 of a differential gear. The wheels 6 and 8 are mounted to turn free on a shaft 7 which is mounted to rotate in suitable bearings 7'. The conical pinion 8 meshes with a bevel wheel 9, which is mounted to rotate on an axle 9' supported by a sleeve 9'', which is secured to the shaft 7. A conical pinion 10 is mounted to turn on the shaft 7 and meshes with the bevel wheel 9. A toothed wheel 11 forming one part with the conical pinion 10 meshes with a toothed wheel 12 secured to a shaft 13,

which is mounted to rotate in suitable bearings 13'. A disc 14, for instance of aluminum or any other suitable material, is secured to the shaft 13 and is mounted to rotate between the poles of a magnet 15. A worm 16 secured to the shaft 7 meshes with a worm wheel 17, which is connected to the watch spring 18. In a preferred construction of my improved apparatus the mileage and speed indicators are driven immediately from the flexible shaft 1. To this end a bevel wheel 31 is secured to a shaft 32 driving said indicators, and meshes with the bevel wheel 2, as indicated on the drawing by dotted lines.

The apparatus of Fig. 1 operates as follows: If the flexible shaft 1 is rotated by the motor not shown in the drawing, by the action of the magnet 15 on the disc 14 this latter is braked, the braking action being transmitted to the conical pinion 10 of the differential gear. In consequence thereof the conical pinion 10 rotates with a lower number of revolutions than the conical pinion 8, causing hereby a swivelling of the bevel wheel 9 and a rotation of the shaft 7. Hereby the watch spring 18 is wound up, until the resistance of the watch spring exceeds the resistance of the braking mechanism. At this moment the disc 14 begins to rotate at a higher number of revolutions, the watch spring is relieved and the movements are repeated in the manner described above.

In Fig. 2 the braking action on the disc 14 instead of being produced magnetically is exerted by means of a pin 19 of leather, cork or any other suitable material, pressed on the disc 14 by a spring 20 and mounted to slide in a suitable guide 21.

Fig. 3 shows a preferred form of braking mechanism, in which the braking action is produced by a fan. In this construction the toothed wheel 11 meshes with a pinion 12' secured to a shaft 22, which carries a toothed wheel 23, meshing with a pinion 24 secured to a shaft 25. The shaft 25 carries a toothed wheel 26, which meshes with a pinion 27 secured to a shaft 28, the shafts 22, 25 and 28 being mounted to rotate in suitable supports 30. The shaft 28 carries fan blades 29, which produce the braking action on the conical pinion 10.

As before remarked, it will be evident that the differential gear represented in the drawing can be changed, and it may be replaced by any suitable equalizing or yielding mech-

anism without affecting the principle of my invention. It is also evident, that any suitable braking mechanism can be used in connection with the said differential gear or 5 other equalizing mechanism without departing from the spirit of my invention.

The watch or clock and the mileage or speed indicator, when jointly driven by my improved apparatus in the manner indicated 10 above can be suitably arranged side by side on the motor car.

I claim—

1. A device of the character described, comprising, in combination, a main spring, a 15 normally rotating member, a differential gear mechanism between said rotating member and spring, means for transmitting motion from said rotating member to said differential mechanism, means for causing a 20 planetary motion of one member of said differential gear mechanism, and means actuated by said planetary motion for winding said spring.
2. A device of the character described, 25 comprising, in combination, a spring, a normally rotating member, a differential gear mechanism between said rotating member

and spring, means for transmitting motion from said rotating member to said differential mechanism, a brake device geared to 30 said differential mechanism and adapted to resist the motion of the differential mechanism, and means actuated by said resistance for winding said spring.

3. A device of the character described, 35 comprising, in combination, a spring, a shaft mounted for rotation adjacent to said spring, a pair of differential gears mounted for rotation on said shaft, a bearing secured to the shaft and carrying an intermediate differential gear in mesh with both of said pair of gears, a normally rotating member, gearing between said normally rotating member and one of said pair of differential gears, 40 means acting on the other of said pair for resisting rotary motion thereof thereby to cause a planetary motion of said intermediate gear and to rotate the shaft, and gearing between said shaft and spring for winding the latter. 45

In testimony whereof I have signed my name to this specification.

KARL HEINRICH MEIER
